CLAIM

The ornamental design for a plug for a battery terminal connector, as shown and described.

DESCRIPTION

FIG. 1 is a bottom, front and right side perspective view of a plug for a battery terminal connector showing my new design;

FIG. 2 is a top, rear and left side perspective view thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a right side elevational view thereof, the left side elevational view being the mirror image thereof; and

FIG. 8 is a cross-sectional view thereof through line 8—8 of FIG. 6.

FIG. 1

FIG. 2

FIG. 3

FIG. 4

FIG. 7

FIG. 5

FIG. 8

FIG. 6
